CLAIM

The ornamental design for a vehicle tailgate, as shown and described.

DESCRIPTION

FIG. 1 is a front left perspective view of a vehicle tailgate according to the present invention.

FIG. 2 is a rear right perspective view of the tailgate shown in FIG. 1.

FIG. 3 is a front elevation view thereof;

FIG. 4 is a rear elevation view thereof;

FIG. 5 is a left side elevation view thereof;

FIG. 6 is a right side elevation view thereof; and

FIG. 7 is a top plan view thereof; and

FIG. 8 is a bottom plan view thereof; and,

FIG. 9 is an environmental front view of the tailgate shown in FIGS. 1-8, shown mounted on a vehicle.

Broken lines form no part of the claimed design, but are instead included to show environmental structure.
